UNITED STATES PATENT OFFICE.

EARL E. EICKMEYER, OF DAYTON, OHIO, ASSIGNOR TO THE DAYTON PUMP & MANUFACTURING COMPANY, OF DAYTON, OHIO, A CORPORATION OF OHIO.

GASOLINE PUMP.

Application filed March 25, 1927. Serial No. 178,180.

My invention relates to gasoline pumps.

It is the object of my invention to provide a gasoline pump in which the interior operating structure may be mounted on several points of support upon the base without attaching the operating structure to the inclosing casing, thereby greatly reducing the cost of production eliminating the usual ring, which is found in most cases, tying the casing and the operating structure together.

It is my object to provide a common base on which the casing rests, the casing being utilized purely for enclosing purposes, while the operative structure is tied to the base independently of the casing.

It is a further object to provide a three-point support on the base rigidly reenforcing the base and tying the structure thereto to prevent movement.

It is an additional object to provide a base so arranged that access to the interior may be readily secured for connecting the pipe from the tank under ground to the operating structure without interfering with the mounting of the structure in its predetermined position upon the base.

It is an additional object of my invention to provide by this arrangement a gasoline pump which may be structurally strong without the necessity of making its casing excessively heavy, as the casing has very little stress or strain to withstand, its function being purely protection and ornamental.

Referring to the drawings:

Figure 1 is a side elevation of the complete structure showing in dotted lines the relative location of the operating structure without the casing;

Figure 2 is a section on the line 2—2 of Figure 1 looking in the direction of the arrows;

Figure 3 is a section on the line 3—3 of Figure 1 looking in the direction of the arrows;

Figure 4 is a section on the line 4—4 of Figure 2;

Figure 5 is a section on the line 5—5 of Figure 4;

Figure 6 is a perspective of the base and cylinder without the casing.

Referring to the drawings, 1 is a heavy base preferably of drawn steel or cast metal, which is provided with a supporting shoulder 2 for supporting the casing 3.

On the interior of the casing integrally

formed as a part of the base are three spaced upwardly and inwardly extending brackets 4 whose inturned ends 5 constitute eyes through which pass the tie-rods 6. The space 7 between these upstanding members 4 is sufficiently large to permit of the attachment of the nuts 8 to the tie-rods 6 and the attachment of the union 9 to the pipe 10 and cylinder pipe 11 to connect the tank with the cylinder 12.

The cylinder itself, generally designated 12, consists of a tube and end members 13 and 14 provided with eyes on the margin thereof through which the staples 6 pass, the bolts being so threaded that the nuts 15 and 16 treded on the stay bolts clamping the end members 13 and 14 of the tubular sleeve constitute the cylinder, thereby providing for a sub-assembly of the cylinder as a unit, which greatly facilitates manufacture, and, after this sub-assembly has been made, it can be dropped in its completed state into position on the base arms 4 by simply inserting the free ends of the tie-rods 6 in the eyes 5 and applying the nuts 8.

Thus, a three point rigid structure is provided which attaches the cylinder in all the mechanism of the pump which rests on top of the cylinder to the base without any attachment of said mechanism to the enclosing decorative casing 3.

This not only eliminates the cast or drawn steel ring, which has been customary as a part of the casing and as a part of the structure between the operating mechanism and the casing, but it greatly facilitates the production of this pump in sub-assembly units, reducing the cost of manufacture and providing a very much more rigid pump which is not affected by any jars or blows which may be imparted to the casing, which are not infrequent in the operation of gasoline pumps at filling stations.

By providing a base casting, end cylinder castings, a cylinder and three tie-bolts, it is possible to secure a very strong and rigid structure with the minimum of expense.

It will be understood that I desire to comprehend within my invention such modifications as may be necessary to adapt it to varying conditions and uses.

Having thus fully described my invention, what I claim as new and desire to secure by Letters Patent, is:

1. In a gasoline pump, a common base, a

pump structure mounted thereon, and a casing mounted on said base independent of the pump structure.

2. In combination in a gasoline pump, of a common base, a plurality of spaced tie-rods mounted thereon, a pump structure mounted on said base and tied thereto by said tie-rods, and a casing mounted on the said base independent of the pump structure.

10 3. In a gasoline pump, a base having a plurality of attaching members spaced from one another, a cylinder mounted on said attaching members, and tie-rods passing through a portion of said cylinder and said 15 attaching members to tie the cylinder and base together.

4. In a gasoline pump, a common base, a cylinder consisting of a cylindrical portion, and end members, tie-rods adapted to tie 20 said end members together on said cylinder, said tie-rods having ends projecting for attachment into said base, means for removably attaching said tie-rods to said base, whereby said tie-rods and said cylinder 25 members may be assembled as a separate unit and then installed upon the base as a complete unit to which they are attached, and a casing mounted on the said base independent of the pump structure.

30 5. In a gasoline pump, a base, a plurality of upstanding spaced arms, three in number, triangularly disposed, a cylinder mounted on said arms and tie-rods passing through portions of said cylinder and said arms for 35 tying the cylinder and the base together.

6. In a gasoline pump, a base, a plurality, of upstanding spaced arms, three in number,

triangularly disposed thereon, a cylinder mounted on said arms, rods passing through portions of said cylinder and said arms for 40 tying said cylinder and base together, and means located within said base, access to which is secured through said arms, placing said cylinder in communication with a remote tank.

45 7. In a gasoline pump, a base having upstanding spaced arms, three in number, equidistantly disposed to one another, the space between said arms and the base being sufficient to permit access to the interior of the base, a cylinder having a cylindrical portion, end members, and tie-rods adapted to attach said end members on said cylindrical portion, said tie-rods being adapted to extend through said arms on said base for 50 attaching the cylinder to the base.

8. In a gasoline pump, a base having upstanding spaced arms, three in number, equidistantly disposed to one another, the space between said arms and the base being 55 sufficient to permit access to the interior of the base, a cylinder having a cylindrical portion and end members, tie-rods adapted to attach said end members on said cylindrical portion, said tie-rods being adapted to extend through said arms on said base for 60 attaching the cylinder to the base, and means on said cylinder consisting of three equidistantly spaced feet adapted to rest on said arms and to receive said tie-rods there- 65 through.

70 In testimony whereof I affix my signature:

EARL E. EICKMEYER.
